DIRECTIONAL RADIO RECEIVER

William P. Lear, North Hollywood, Calif., assignor, by mesne assignments, to Lear, Incorporated, Grand Rapids, Mich., a corporation of Illinois

Continuation of application Serial No. 291,807, August 25, 1939. This application August 24, 1943, Serial No. 499,754

14 Claims. (Cl. 250—11)

This invention relates to receiver arrangements for radio guidance systems for mobile craft, particularly aircraft. The present application is a continuation of my copending application Serial No. 291,807 filed August 25, 1939, and assigned to the same assignee as the present case.

The receiver arrangement of the present case is designed to operate in conjunction with a pair of non-directional radio signal transmitters arranged in spaced relation along an approach path such as an airport runway. The receiver arrangement continuously indicates to the pilot his exact relative lateral position with respect to the airport in general, and his exact position with respect to the approach path to the runway. As described in my said copending application, with the system of my invention, the pilot may approach the runway directly on the shortest route and without any trial flight since he clearly knows his orientation with respect to the airport and runway course. The two indicator needles of the receiver are in line with the center-zero index when the pilot is on-course with the runway. As he passes over the outer transmitter, the "out" indicator needle reverses by 180°. This serves as a marker indication to appraise him of his exact distance from the edge of the runway. As the pilot continues on-course to the runway, the second or "in" needle will reverse by 180° when he passes over the inner transmitter station. No separate marker beacons are thus necessary. The pilot is then ready to glide down to a landing using any suitable vertical guidance means.

Drifting from the predetermined approach course is accurately detected through the dual indicator readings, and is readily compensated for the pilot. No reliance on directional gyroscopes or other flight instruments is necessary. The results are foolproof and independent of adverse weather conditions. There are no successive receiver tuning changes or other distracting duties required of the pilot with the system of my invention. After the initial tuning operation, the dual indicator arrangement is continually effective in guiding the pilot in the manner set forth.

In a preferred form of my invention I employ two transmitter stations having the same carrier frequency. The radiation by the stations is successively switched on and off at predetermined intervals. The two stations are differentiated with either separate audio frequency tone modulations, or with one station being tone modulated and the other unmodulated. A dual automatic directional indicator system is used aboard the mobile craft. In one form the receiver system has two

5 separate rotatable directional antennae, one corresponding to each of the two field transmitters. An automatic radio control unit is used to individually orient the two directional antennae to their null signal positions with respect to the radio transmitters.

10 The directional antennae are operative over a 360° range. A separate automatic control radio unit may be used for each of the rotatable loop antennae. In a preferred embodiment, I use a single automatic radio control unit connected successively to each of the two rotatable directional antennae in correspondence with the intervals of radiation of the transmitters as controlled by the audio tone modulations thereof. A composite indicator is used, having two needles, one coupled to each of the rotatable antennae. The two needles point out the actual direction towards each of the field transmitters, and appraise the 15 pilot of his exact lateral position with respect to the airport and the approach path to the runway as will be described in more detail hereinafter.

20 The present invention is applicable for guiding a marine vessel into its slip, such as during fog conditions. In this case, the two radio transmitters are placed on land in line with the direction which the vessel is to enter the slip. The pilot employs the same approach equipment described in connection with the aircraft guidance and is 25 accurately guided into the slip despite river current or zero visibility conditions. Anti-collision devices can be used for safety reasons when there is sole reliance on the radio guidance in docking the vessel.

30 35 It is therefore among the objects of the present invention to provide a radio receiver arrangement for indicating to the pilot his exact relative position with respect to two spaced transmitter stations; to provide such a system including two 40 directional antenna, means for orienting the antenna with respect to received radio signals, a directional control unit, a composite indicator having needles operatively associated with each antenna, and means selectively operable in response 45 to the received radio signals for intermittently connecting each antenna and its orienting means to the directional control unit; to provide a dual radio directional guidance system for giving substantially continuous bearing indications on each 50 of a pair of spaced radio transmitters; and to provide a novel radio instrument approach system employing a plurality of rotatable directional antenna automatically controlled from a unitary directional control receiver.

55 These and further objects of my present in-

vention will become apparent from the following description and accompanying drawings.

In the drawings:

Fig. 1 is a diagrammatic arrangement of a complete receiver system incorporating the principles of the present invention.

Fig. 2 illustrates one form of the dual indicator mechanism, being partly in section.

Fig. 3 is a schematic electrical diagram of a preferred circuit arrangement for the automatic directional receiver equipment corresponding to the diagrammatic showing in Fig. 1.

Fig. 1 is a diagrammatic representation of a complete receiving system for a radio guidance system, employing spaced transmitter stations such as described in connection with Figs. 4 to 6 of my said copending application. Two separate rotatable loop antennae 120 and 120' are mounted upon individual shafts 121 and 121'. Slip rings 122 connect the winding of loop antenna 120 to leads 123 for connection to the back contacts of relay armatures 124 and 125. Similarly slip rings 122' connect the winding of loop antenna 120' to leads 123' for connection to the front contacts of relay armatures 124 and 125.

Relay armatures 126 and 127 are employed for selectively connecting the control motor drive arrangement for the loop antennae to the receiver. Relay solenoid 130 is arranged to actuate relay armatures 124 to 127 when energized by currents from the automatic directional receiver system connected thereto through leads 129. The position of loop antenna system 120 is controlled by reversible motor 131 connected to loop shaft 121 through electromagnetic clutch 132 and gearing 133, 134. Motor 131 is connected in parallel with magnetic clutch 132 and in turn to the back contacts of relay armatures 126, 127 by leads 135.

The motor control system of rotatable loop antenna 120' comprises motor 131' connected to shaft 121' through electromagnetic clutch 132' and gears 133', 134'. Motor 131' and clutch 132' are connected across front contacts of relay armatures 126, 127 through leads 135'. Relay armatures 126, 127 are connected to the motor relay system of the automatic directional unit through connection leads 136. The preferred construction of the rotatable loop antennae 120, 120' and their associated electromotive drives is preferably in accordance with the disclosure of my Patent No. 2,308,521 issued January 19, 1943 entitled "Automatic radio direction indicator."

The automatic radio directional receiver schematically illustrated in Fig. 1 is preferably similar to that disclosed in my said patent modified to perform the radio guidance operation in connection with the two loop systems. Relay armatures 124 through 127 are normally attracted to the upper or front contact position shown through normal continuous energization of relay solenoid 130. With the relay armatures in the upper position, loop antenna 120' is in circuit connection with the automatic radio directional circuit through leads 128, and its associated motor and clutch 131', 132' is also connected thereto through leads 136.

The receiver system normally operates in this position as an automatic directional receiver indicating the bearing on any radio station tuned in by the receiver unit. A loop position transmitter unit 140' is employed to transmit the angular position of loop antenna 120' to remotely located meter 145. A direct current Selsyn telemetering arrangement incorporating a battery 141' and three-wire cable 142' is used in the embodiment

of Fig. 1. Needle 2 of meter 145 is associated with rotatable antenna 120' and indicates its angular position on the scale of meter 145.

When the automatic receiver is to be used for instrument approach in conjunction with spaced field transmitter stations such as indicated in Figs. 1, 4 and 5, of my copending application Serial No. 291,807, the directional receiver circuit is tuned to the predetermined frequency of the transmitters. In this case, directional antenna 120' will be moved to point so that its null signal position corresponds to the direction towards the unmodulated transmitter station and "out" indicator needle 2 of meter 145 will thus point towards the unmodulated station. The automatic angular orientation of loop 120' through control motor 131' is effected during the transmission interval of the unmodulated station, within one-third of a second in the preferred case.

During the transmission of the "in" station, the predetermined audio frequency modulation of the radio frequency carrier wave at such station will cause relay 130 to be deenergized in a manner to be described, and relay armatures 124 to 127 will drop to the back contact position. Thus, while the tone modulated station is being received, antenna system 120' is automatically disconnected and antenna 120 is connected to the directional receiver. A separate telemetering system is connected to shaft 121 of loop antenna 120 so that needle 1 of indicator 145 will accurately point out the position which loop antenna 120 is made to assume, being a bearing on the tone modulated station. D. C. Selsyn transmitter 140 is energized by battery 141 and connected to meter 145 through cable 142. Loop antenna 120 is automatically moved so that its null signal position accurately corresponds to the direction towards the tone modulated station.

Indicator 145 has an "in" needle 1, and "out" needle 2. The zero index 0 corresponds to the axis of the aircraft. After adjustment of the tuning of the directional receiver to the common carrier frequency of both transmitting stations, instrument approach guidance as described in connection with Fig. 1 of my said copending application Serial No. 291,807 is effected. The alternately radiating transmitting or field stations cause relay solenoid 130 to correspondingly switch rotatable antenna system 120' and alternately system 120 out of and into circuit relation with the automatic directional receiver. The arrangement is such as to successively move the respective antennae and their associated needles on indicator 145 to point out, preferably to within 1° of arc, the direction towards the respective field stations.

The preferred automatic directional receiver, common to both rotatable loop antenna systems, is shown in block diagram in Fig. 1 and corresponds to Fig. 1 of my Patent No. 2,308,521. The directional receiver is remotely positioned with respect to the rotatable loop antennae and the non-directional antenna, as indicated by the broken lines 138. Non-directional antenna 150 is connected to primary winding 151 which is coupled to secondary winding 152 of the radio frequency transformer coupled to radio frequency receiver and audio frequency detector 153. Variable condenser 154 is shunted across secondary winding 152 and is adjusted to tune-in the proper radio frequency to be received for radio guidance or automatic direction finding as required.

The radio frequency signals impressed upon

radio frequency receiver 153 are demodulated and impressed upon audio frequency amplifier 155. During the transmission interval of the unmodulated transmitter, no separate tone or audio frequency relay signal is derived and relay solenoid 130 remains normally energized attracting relay armatures 124 through 127 as indicated in Fig. 1. However, during the transmission interval of the radio transmitter modulated by a relay tone, say of 75 cycles, a corresponding 75 cycle note will appear at the output of audio frequency amplifier 155. The 75 cycle tone is impressed upon relay filter 158 which prevents the passage of other frequency signals and passes the predetermined relay frequency of 75 cycles in the present example.

The output of filter 158 is connected to relay rectifier 159, the output of which is connected to solenoid 130. A preferred arrangement for the actuation of solenoid 130 is such that the solenoid is normally energized connecting loop antenna system 120' to the directional receiver. Upon reception of a radio signal bearing a substantial 75 cycle (or other predetermined frequency) signal relay 130 is arranged to be deenergized and switch the directional receiver from directional antenna system 120' to directional antenna system 120. It is to be understood that the relaying action wherein the predetermined (75 cycle) note causes energization of relay 130 instead of deenergization thereof may equally well be employed. Detailed circuit diagram Fig. 3 illustrates the arrangement for effecting the herein described operation of relay solenoid 130 by the 75 cycle signal.

The loop winding relay armatures 124, 125 are coupled to the loop radio frequency amplifier 160 through radio frequency transformer 161, 162 by transmission cable 128 which is preferably of low impedance. A variable condenser 163 in shunt with the secondary winding 162 is used to tune-in the desired radio station. All the tuning controls such as condensers 154 and 163 are preferably mechanically ganged together to provide the unitary tuning control. It is to be understood that a plurality of receiving bands may be employed to permit operation of the receiver system over a wide range of radio transmission frequencies. If a particular frequency is used for effecting the instrument approach to an airport, a rapid switch over means to bring the receiver to that frequency may be provided, as will be understood by those skilled in the art.

In describing the operation of the automatic directional receiver section, which lies to the right of broken lines 138, reception by one of the loop antennae is assumed. With the position of relay armatures 124 through 127 shown in Fig. 1, loop antenna 120' and its associated control motor circuit are connected to the automatic receiver. In accordance with the automatic receiver used in the system of the present invention and described in detail in my Patent No. 2,308,521, a loop control signal is provided dependent upon the received loop antenna signal, to operate the motor drive for the loop antenna and rotate it to its null position with respect to the oncoming radio signals. The normal or stable position of the loop antenna is at the null or electrical neutral position with respect to the oncoming radio signals from the associated transmitted station, giving an exact angular indication of the direction to the transmitter of the radio signals. In the present case, the unmodulated transmitter is assumed to be radiating for controlling the ori-

tation of loop antenna 120' and needle 2. When the modulated transmitter station is transmitting, loop antenna 120 instead is connected to the system, resulting in a similar electrical action.

When the angular position of the loop antenna 120' is changed from null during approach maneuvers, the radio signal is picked-up by the loop and impressed upon amplifier 160. The magnitude and phase of this signal depends upon the amount of the off-null angular position of the loop and the direction of the transmitter to the right or left thereof, respectively. A local generator 164 of an audio frequency current, preferably of the order of one hundred cycles, is used to modulate the radio signals derived from the loop antenna and produce a resultant tone modulated radio signal. I prefer to use a tone signal of 102.5 cycles as indicated in the drawings, but a different frequency may instead be used so long as it is different than the signal for relay 130. Loop signal modulator 165 schematically designates the modulation stage, preferably a balanced modulator, for combining the loop signal of 160 with the tone signal of 164.

The resultant tone modulated radio signal at 160 has a magnitude and phase dependent upon the off-null position of receiving loop antenna. The tone modulated signal is then suitably combined with the non-directionally received signal from antenna 150 by a coupling means, such as coupling coil 166 linked with secondary winding 152 of the input transformer to radio frequency receiver 153. The nature of the radio signal impressed upon the input of amplifier 153 is described in more detail, in connection with Fig. 3 of my said Patent No. 2,308,521. The superposition of the non-directional radio signals with the locally modulated loop signals provides a resultant radio signal with the 102.5 cycle tone component having a magnitude and relative phase dependent upon the off-null position of the loop antenna with respect to the oncoming wave. Radio frequency receiver 153 may be a tuned radio frequency circuit or a superheterodyne circuit. The receiver unit 153 contains a demodulator or detector for the audio frequency components of the amplified radio signals. The audio frequency signals at the output of unit 153 comprise modulations of the original radio wave plus the 102.5 cycle tone or control signal obtained when the loop antenna is off null.

An audio frequency amplifier 155 is connected to the output of receiver-detector unit 153. Amplifier 155 supplies audio unit 156 with sufficient energy for operating headphones connectable to jack 157 at the output thereof. The output of audio frequency amplifier 155 is also connected to a separate control signal amplifier 167 through a suitable phase shifting net-work 168 and 102.5 cycle pass filter 169. The 102.5 cycle tone signal is thus filtered out from the output of audio frequency amplifier 155 and amplified a substantial degree for use as a control signal to operate the relay control tube system indicated at 170. The relay control tube system is energized by both the control signal from amplifier 167 as well as the correspondingly amplified tone signal obtained directly from generator 164 and intermediate tone amplifier 171. Details of the operation and interrelation of the respective control signals and the relay control tube system 170 are described in further detail in connection with Figures 4 and 4a of my Patent No. 2,308,521.

Control relays indicated at 172 comprise solenoids 173 and 174 connected to the relay control

tube system 170. Solenoids 173 and 174 are selectively energized from control system 170 in accordance with the angular position to the right or left of the loop connected, with respect to the direction of the oncoming radio waves. When relay 173 is energized, it attracts its armature 175 to close the electrical circuit through ground including its front contact, battery 177, and the loop motor. When antenna 120' is connected to the system, motor 131' is thus energized. Motors 131 and 131' are connected in a predetermined manner to operate in the direction to rotate loop antennae 120 and 120' respectively towards their null signal position through their shafts 121 and 121' and associated gearing. Energization of either relay 173 or 174 is determined upon the direction of the angular deviation of the connected loop antenna (120') from its null position with respect to the radiating station so that the proper counterrotation of the associated motor (131') will occur to bring the loop antenna to the null signal position.

Relay 173 remains energized until the loop antenna is rotated to reach its null position, whereupon the control signal derived from the loop signal impressed upon amplifier 160 is so reduced in value or obliterated as to cause relay armature 175 to drop back to its neutral or back contact position, deenergizing and stopping the associated motor. Electromagnetic clutches 132 and 132' are electrically shunted across their motor energization circuits to immediately disconnect the associated motor from the loop antenna, insuring a rapid stop of the loop rotation at the time of motor deenergization, and eliminating the possibility of overshooting or overdriving by the motor due to its mechanical inertia. The frictional forces of the gearing and the bearings of the loops are generally sufficient to quickly stop the loop rotation.

In practice I have constructed systems in accordance with the present invention which automatically operate the loops and therefore the associated bearing indicators at a rate of 180° and more per second. The accuracy of the resultant bearing may readily be made within 1° of arc, i. e. the actual directional indication on each radio transmitter being correct to within 1° or less. The bearing indications are on a 360° dial and move to the stationary bearing position through the shorter angular path. I prefer a rate of indication of about 125° per second for the one-third of a second transmitter radiation periods.

When the loop antenna reaches, or is substantially at, its null signal position a zero or substantially zero magnitude radio frequency signal is impressed upon radio frequency amplifier 160 for modulation at 165 by the generated tone signal from 164. The magnitude of the control signal from amplifier 160 accordingly is also zero, or substantially zero at that time, and control relays 172 are in the deenergized position shown. The loop accordingly remains stationary when it is at its electrical signal null position with respect to the direction of the oncoming waves. This position corresponds to the geometric position of the loop where the plane of the open face thereof is perpendicular to the direction of the oncoming radio waves.

Should the aircraft carrying the loop antenna deviate from this direction the loop will be energized by the oncoming radio signal from the transmitter, and impress it upon amplifier 160 with a magnitude and phase relation correspond-

ing to the altered direction thereof. Should the deflection of the aircraft cause the loop to receive a signal of phase corresponding to that which energizes solenoid 173, the above described operation of the loop motor is repeated to bring the loop to the new null signal position. Should, however, the aircraft turn so that the loop is deviated in the opposite angular direction, the phase of the control signal impressed upon relay control tube system 170 will be different by 180° and energize solenoid 174 instead.

When solenoid 174 is energized, its armature 176 is attracted to the front contact to electrically complete the connected loop motor circuit including its associated clutch, ground, and battery 177. Electromagnetic clutch 132' is thereupon immediately engaged and motor 131' is rotated in the direction opposite to that corresponding to its energization by solenoid 173 when loop system 120' is in connection with the receiver as shown in Fig. 1. Motors 131 and 131' are reversible in the present case, and are not necessarily a direct current type. Relay armatures 175 and 176 are arranged so that the direction of current flow through the connected motor is selectively reversed to cause the motor to rotate its associated loop towards its null signal position in the shorter path of rotation. Thus, when solenoid 174 is energized, the motor will rotate in a direction opposite to that due to energization of relay 173.

An important feature of the preferred automatic directional receiver resides in the fact that, for any bearing, the loop antennae are at their electrically neutral and geometric null positions, and remain stationary for the duration of the bearing. Furthermore, no sense or directional ambiguity occurs, and the null position which the loop assumes is accurate for any bearing on the transmitters. Pointer 2 of indicator 145 moves in exact correspondence with loop antenna 120' and is arranged to point to the center zero position 0 shown on the dial, when the open plane of loop 120' is perpendicular to the longitudinal axis of the aircraft. Similarly, pointer or needle 1 moves in exact correspondence with loop antenna 120, pointing to center zero when the plane of loop 120 is perpendicular to the flight direction.

The accuracy of indication is independent of the position of indicator needles 1 and 2 since any reading thereof corresponds to an electrical null position of loop antennae 120 and 120', and no balancing of electrical parameters or signal components are required to maintain the readings. The interpretation of the readings is readily apparent to the pilot, and he effects an instrument approach as described in connection with Fig. 1 of my said copending application Serial No. 291,807.

In Fig. 2 I have diagrammatically illustrated components of one form of dual indicator 145. A common housing 180 encloses the direct current Selsyn movements for both needles 1 and 2 having corresponding toroidal or annular actuating coils 181 and 182. Coil 181 is connected by leads 184 to three-wire cable 184' which in turn is connected to a direct current loop position transmitter of one loop system. Annular winding 182 is similarly connectable by leads 183 to three-wire cable 183', for connection to the direct current loop position transmitter of the second loop system. Three-pole double-throw switch 185 is used to connect leads 183 with cable 183' as shown in dotted during the double indicator instrument

approach operation of the system so that both needles 1 and 2 of meter 145 are independently controlled.

Indicator needle 1 is connected to central spindle 186 pivoted in end bearing 187. Magnetic core 188, shown in dotted, is secured to spindle 186 and arranged to magnetically coact with the interior of annular winding 181 in the usual telemetering manner. Indicator needle 2 is coupled to the end of tube 190 concentric about spindle 186. Tube 190 is rotatable on diagrammatically indicated bearing 191 for independent rotation with respect to spindle 186 of needle 1. Magnetic core 192, shown dotted, is mechanically secured with rotatable tube 190, and is magnetically coactable with annular winding 182. Indicator needles 1 and 2 are coaxial and independently controlled to assume the angular positions of the two loop antenna systems during the instrument approach maneuvers described. A casing 193, having a flange 194, fitted within the open end of housing 180, encloses indicator needles 1 and 2 and contains the scale for the indications. A transparent window 195, such as glass, is fitted into the top end of enclosure 193.

When the dual receiver system is to be used for taking normal directional bearings on only one transmitter station and not for the described two-station instrument approach maneuvering, three-pole switch 185 is thrown to the position drawn in solid lines in Fig. 2 connecting annular windings 181 and 182 in parallel. Both indicator needles 1 and 2 then act in unison, one above the other, and each assumes the same angular position on the scale of meter 145. For ordinary automatic directional operation, both sections of the meter are connected in parallel with one of the loop position transmitters and give the same reading.

Accordingly, when the dual indicator of Fig. 2 is in circuit with a dual receiver system in accordance with the present invention, three-wire cable 184' connects to the position transmitter of the loop antenna normally in circuit with the receiver, and three-wire cable 183' to the loop position transmitter of the other antenna. For example, if used in the receiver system of Fig. 1, cable 184' would correspond to cable 142', connecting to position transmitter 140' of loop antenna system 120' normally connected to the receiver through relay armatures 124 to 127; and cable 183' would correspond to cable 142 connecting to position transmitter 140 of antenna system 120. Three-pole switch 185 is operated to the solid position for both needles of indicator 145 to give a single reading when the automatic directional system is used for radio guidance in general, and is connected to the dotted position when the pilot is ready for instrument approach to a runway having stations corresponding to T₁ and T₂ of Fig. 1 of my copending application Serial No. 291,807 when both needles become independently operative in the manner described.

Fig. 3 is a detailed schematic electrical diagram, partially in block form, of a commercial form of the automatic receiver system constructed in accordance with the principles of my present invention. Relay system 124 through 127 selectively connects the two loop antennae system 120 and 120' to the receiver as shown in Fig. 1. Fig. 3 is a specific electrical showing of the system shown generally in Fig. 1, and represents a preferred embodiment thereof though not limited thereto.

Signals from the rotatable loop antenna in 75 audio output circuit. Thus 75 or less cycles, or

circuit with loop transmission cable 128 are impressed upon primary winding 161 of the loop radio frequency input transformer, secondary winding 192 of which is shunted by tuning condenser 163 and connected to the control grid of radio frequency amplifier pentode 200 for amplification and introduction to the control grids of balanced modulator stage 165. The gain of loop amplifier 236 is manually controllable by rheostat 201 connecting the cathode thereof to ground. The anode of amplifier 200 is energized through a shunt radio frequency choke coil 202 connected to the B supply.

The output of loop amplifier 200 is coupled to 15 the control grids of tubes 203, 203' of modulator 165 through coupling condensers 204. The cathodes of tubes 203, 203' are tied together and connected to ground through by-pass condenser 205 and biasing resistance 206. An audio frequency oscillator 164 comprising two triodes 207, 207' is arranged to generate an audio or tone frequency current of a relatively low frequency. The control grids of triodes 207, 207' are coupled to the anodes thereof by condensers 208, 208'. Cathodes of the oscillator triodes are tied together and connected to ground through biasing resistor 209.

Resistors 198 and 198' are coupled between the grid electrodes of triodes 207, 207' and ground. 30 Intermediate taps on the resistors 198 and 198' couple a portion of the available alternating current tone energy from oscillator 164 to the grids of modulator triodes 203, 203' through coupling resistances 196 of about one megohm each and 35 through coupling condensers 197, 197'. Further resistances 199, 199' normally connect grid coupling condensers 197, 197' to ground to stabilize the grid circuits of tubes 203, 203'.

The actual frequency of the tone current generated by oscillator 164 as used in the system is optional, and may for example lie anywhere in the audio frequency spectrum, or even higher. Practically, however, the tone frequency should be chosen so as to efficiently pass through the 45 respective radio frequency circuits as side-bands, and the audio frequency circuits as well, be audible to the pilot when present and differ from the relaying tone from the field transmitters. It is also desirable to prevent interference with the 50 intelligibility of the aural messages of the radio signals. An important consideration is to minimize any effect due to the sound modulations of the radio wave upon the control circuit. I have found that a control signal in excess of 200 to 55 300 cycles contains sound modulation components after filtering out for control purposes.

Modulation "kicks" occur when the sound frequencies of the radio signals coincide with the control frequency, and interfere with the 60 stability of the directional indications. A tone frequency of the order of 100 cycles is sufficiently high to efficiently pass through the radio and audio frequency channels of the system, sufficiently low to not interfere with the intelligibility 65 of the audio frequency modulations of the radio signal, and is not effected by modulation kicks. A practical tone frequency in this range I found to be a tone of 102.5 cycles, as indicated in the figures. This frequency is satisfactory when the 70 loop relaying frequency of the tone modulated transmitting station is 75 cycles. The field transmitter tone should differ sufficiently from the receiver control frequency, 102.5 cycles in the present case, to be properly filtered out of the audio output circuit. Thus 75 or less cycles, or

150 or more cycles per second are satisfactory for the tone modulated transmitting station when 102.5 cycles are used in the receiver.

Control grid electrodes of modulator triodes 203, 203' accordingly simultaneously receive the audio frequency tone signal from oscillator 164 and the radio frequency signal picked up by the connected directional antenna. The output of modulator stage 165, obtained through the anodes of tubes 203, 203', is connected to opposite sides of radio frequency winding 166 coupled to secondary winding 152 of the non-directional antenna circuit. The anode supply for modulator tubes 203, 203' is obtained through a center tap on winding 166 connected to the common B supply as indicated.

The frequency of the loop modulated signals is the sum and difference of the received radio signals and the low frequency oscillator tone signal. The simultaneous induction of the non-directional radio frequency signals with the tone modulated loop signals upon winding 152 produces a resultant signal upon the control grid of radio frequency amplifier 210. The non-directional signal from antenna 150 serves as a reference signal or sense determinator, so that the right or left sense of the loop antenna signals is established for further control action on the orientation of the loop antennae. Thus proper functioning of the automatic directional receiver is assured, quickly bringing the connected loop antenna back to its null signal position to give accurate bearing indications on the field station transmitting.

The signals impressed upon the control grid of radio frequency pentode 210 are amplified and transmitted through output radio frequency transformer 211 having its secondary winding tuned to resonance by variable condenser 212 shunted there-across. The output of transformer 211 is coupled to intermediate grid electrode 215 of the radio frequency mixer stage 220 through coupling condenser 216. Radio frequency mixer stage 220 is shown as a hexode wherein grid electrode 217 adjacent to the cathode is energized by a signal emanating from a local beat frequency oscillator 221 operated in the usual manner for superheterodyne reception. The anode and screen grid operating potential for stage 220 is supplied through respective resistors 222, 223.

The output of radio frequency mixer stage 220 comprises primary winding 225 of a step-down intermediate frequency transformer shunted by adjustable condenser 227 for resonating the coil at the intermediate frequency, such as 455 kilocycles. Transformer 225, 226 is a step-down transformer so that a long low impedance transmission line 230 may be used to permit placing the intermediate frequency and audio frequency amplifier equipment remote from the radio frequency section including directional and non-directional radio signal amplifiers, and loop modulator stage. Transmission cable 230 is an electrically shielded low impedance cable terminating in a correspondingly low impedance primary winding 231 of step-up intermediate frequency transformer 231, 232. Secondary winding 232 of the terminating transformer is shunted by a resonating adjustable condenser 233 to tune the transformer to the intermediate frequency used.

The output of step-up intermediate frequency transformer 231, 232 is connected to the grid electrode indicated at 234 of the input stage of two-stage intermediate frequency amplifier 235

shown in block diagram form. The anode indicated at 236 of output stage of intermediate frequency amplifier 235 is connected to transformer 237, the primary and secondary windings of which are respectively shunted by adjustable condensers 238 and 239 and tuned to the intermediate frequency. An audio frequency detector stage 240 has its control grid connected to the output of intermediate frequency transformer 237 for demodulating the signals and produce corresponding audio frequency currents across cathode resistor 245 connected to ground.

Both the radio signal tone modulations as well as the local control signal if present, produce a corresponding audio frequency signal across resistor 245 by the detector action. The anode of detector 240 is connected to the common B supply as indicated. Condenser 246, between the cathode of detector 240 and ground, by-passes the higher order frequency currents from the audio frequency path. The derived audio frequency signals are coupled to audio frequency pentode amplifier stage 250 by coupling condenser 248. The anode circuit of amplifier 250 comprises resistance 251 connected to the common B supply and is coupled to the control grid 252 of a second audio frequency amplifier stage 255 through coupling condenser 253. Second audio frequency amplifier stage 255 is resistance-capacity coupled by anode resistor 256 and coupling condenser 257 to a further two-stage audio frequency amplifier 260.

It is to be understood that both the original audio frequency signal modulations on the radio carrier wave and the control or tone signal amplified together therewith, are impressed upon two-stage amplifier 260 for further amplification to an appreciable signal level. The output of amplifier 260 is coupled to the aural amplifier indicated at 270, to the output of which earphones 275 are connected. The pilot adjusts the aural level of the signals by a separate manual control in aural unit 270. The output of audio frequency amplifier 260 is also coupled to amplifier stages 280 and 290 for selecting and further amplifying the 102.5 cycle loop motor control signal and impressing it upon relay control system 170, and also to pass filter 350 for controlling the selective connection of loop systems 120 and 120' to the receiver, through transmitted relaying signals.

The output of audio frequency amplifier 260 is coupled to the control grid 281 of amplifier stage 280 by coupling condenser 261 and phase shifting net-work 262, 263. Resistor 265 is shunted across phase shifting network 262, 263 connecting the control grid of stage 280 to ground. The relative impedance of resistor 262 and condenser 263 is chosen to suitably shift the phase of the 102.5 cycle control signal to be impressed upon control grid 281 to compensate for any misphasing thereof caused in the circuits prior to that point. Such phasing is made to cause the phase relation of the signal arriving at the input of tube relay control system 170 to be substantially in-phase or 180° out-of-phase with the correspondingly impressed tone signal from amplifier 171.

The control signal impressed upon control grid electrode 281 of pentode amplifier stage 280 is amplified in a conventional manner. The output of amplifier 280 is impressed upon control grid 291 of a further amplifier stage 290 through coupling condenser 292. A tuned filter 285, 288 is used to filter out other signals or modulations

than the 102.5 cycles, and most efficiently pass this signal frequency. Other filter arrangements than the shunt choke coil 285 and condenser 288 may be used. Amplifier stage 290 comprises a triode tube, the anode circuit of which includes primary winding 292 of audio frequency coupling transformer 295. Secondary winding 296 of transformer 295 is shown schematically coupled to the input of the relay control system 170. The output of 102.5 cycle amplifier 171 is impressed upon relay control system 170. Fig. 4 of my said Patent No. 2,308,521 illustrates a preferred circuit arrangement for the relay control tube system 170.

Variations in the level of the received radio signals are compensated for by an automatic level control. A further arrangement of the system maintains constant the anode or B voltage supply for critical parts of the circuit despite variations in the supply voltage thereto, to insure uniform sensitivity and operation of the loop motor controls and associated electronic relay system. A voltage regulator tube 360 is connected between a particular point 305 and ground, to maintain a predetermined and uniform operating voltage supply for the critical part of the electronic control arrangement which includes the anodes of oscillator 164 through lead 304, the amplifier 171 through lead 307 and electronic relay system 173 through lead 306.

An automatic level or volume control arrangement is provided through rectifier 310 fed by an intermediate frequency signal tapped from intermediate frequency output anode 236 through coupling condenser 311 to anode 312 thereof. Delayed automatic volume control (D. A. V. C.) action is obtained by providing a positive biasing voltage raising the potential of cathode 313 to delay the biasing control action till the received radio signals reach a predetermined level. Anode 312 of rectifier 310 is connected to the control grids of the respective radio frequency, intermediate frequency and audio frequency stages of the circuit to establish a substantially flat and uniform amplification response of the signals through the system.

Coupling resistances 315, 316, 317, 318 are used in this level control circuit, and control grid 234 of the intermediate frequency amplifier is connected thereto by direct connection 319 through secondary winding 232. The second stage of the intermediate frequency amplifier 235 is preferably also controlled by the level control circuit described. The inclusion of at least the first audio frequency amplifier stage 250 in the signal control circuit from rectifier 310 results in a very flat overall response despite wide signal level changes in the received radio waves.

A manual switch 320 is provided at the cathode of the first radio frequency amplification stage 210 to disconnect the automatic volume control effected thereto through resistor 315, for manually controlling the bias through variable resistor 322 in the cathode circuit. This manual volume control is useful for communication or reception of radio range signals. A further switch 325 is provided for continuous wave beat frequency oscillator 330 to connect it to audio frequency detector stage 240 for heterodyning continuous waves. Continuous wave oscillator 330 is used for audibly perceiving continuous wave transmission and serves as a signal "station finder" for such stations. The normal connection of switch 325 to ground contact 326 is schematically indicated for rendering oscillator 330 ineffective

as a heterodyning means, which connection is used for phone reception. By ungrounding switch 325, oscillator 330 becomes effective for heterodyne reception of continuous waves.

A direct current millimeter 340 is connected between the output of automatic volume control stage 310 and ground, through series resistance 345. Meter 340 serves as a measure of the automatic level biasing current and indicates the relative signal strengths of received radio signals. Meter 340 thus serves as a relative distance or millimeter. Flight toward a station increases the signal strength and therefore the indication on meter 340. Flight away from a station correspondingly decreases its indications.

The audio frequency output of amplifier 260 is connected to a highly selective filter 350 by leads 349 to segregate the radio relay tone, 75 cycles in the present embodiment, from other audio frequency signals which may be present. Pass filter 350 is selected to pass efficiently the chosen relaying frequency. The actual construction of pass filter 350 is optional, and I have illustrated one form which it may assume in practice. A resonant shunt path comprising inductance 351 and capacitance 352 tuned to the frequency to be passed, comprises the initial section thereof. A series inductance 353 connects shunt path 351, 352 to a further shunt path 354, 355. The output of filter 350 contains series inductance 356. Filter 350 is specifically designed to reject the 102.5 motor control frequency which orients the loop antennae. The invention is not limited to any particular frequency for either the loop motor control or the relay switching control. The output of filter 350 is coupled to a rectifier amplifier stage 360 through coupling condenser 357. The 75 cycles signal is impressed upon detector anode 358 having shunt resistor 359 to ground across which the rectified component is built up. The cathode of stage 360 is positively biased with respect to ground by battery 361. Control grid 363 of the triode section of tube 360 is coupled to diode anode 358 through resistor 362. A bypass condenser 364 connects grid 363 to ground.

Relay solenoid 35 is connected between anode 366 and the B supply for stage 360. Normal anode circuit current passes through solenoid 365 when no relaying tone signal is impressed upon stage 360 from filter 350. This current is sufficient to energize the solenoid 365 and attract armature 370 against contact 369 as shown in dotted. In this position, relay contact 369 is connected with armature 370, and energization of relay solenoid 130 is maintained through local source 373. Relay armatures 124 through 127 accordingly are normally against their front contact position as shown in Fig. 1, connecting loop antenna system 120' to the directional receiver circuit.

When the tone modulated transmitter station is operating and the audio frequency tone modulation thereof is present in the receiver, the relaying tone, namely the 75 cycles frequency signal, passes through filter 350, is rectified by stage 360 and causes a substantial negative bias upon control grid 363 thereof. The negative bias chokes off the normal anode current flowing through solenoid 365, and permits spring 372 to draw armature 370 from contact 369 against backstop 371 as shown in solid in Fig. 3, opening the circuit between battery 373 and solenoid 130. When the 75 cycle relaying signal is received, switch-over relay 130 is accordingly deenergized in the described embodiment. When relay solenoid 130

is deenergized armatures 124 through 127 drop to their back contact position shown in Fig. 3, disconnecting loop system 129' from the directional receiver and connecting loop system 120 thereto.

The switch-over or relaying action by solenoid 130 occurs when the tone modulated field station is radiating. The automatic loop orientation by the directional receiver is made effective on loop antenna system 120 for the duration of transmission of the tone modulated station. Loop antenna 120 is quickly moved to its null signal position with respect to the tone modulated station by stable action, bringing the local 102.5 cycle signal below the value to cause operation of loop motor 131. Indicator needle 1 of indicator 145 (Fig. 1) corresponds to loop antenna 120 and to the tone modulated station as previously described. Needle 1 remains at the position which antenna 120 assumes after antenna system 120 is unswitched from the directional receiver, upon cessation of the tone modulated signal and transmission of the unmodulated signal.

In accordance with the operation of the receiver system described, when the tone modulated station ceases transmitting and the unmodulated station starts transmitting, loop antenna system 120 is disconnected from the receiver circuit and remains stationary while the other antenna system 120' is placed under the control of the directional receiver. Signals from the unmodulated station orient loop 120' to point thereto. Needles 1 and 2 remain stationary during the quiescent periods of the transmitters. Since approach maneuvers take place at a speed in the range of 80 to 120 miles per hour, a switching rate of about one-third of a second for the field transmitters is preferred. I have found during extensive experimentation that a rate of switching less than one-half of a second gives indications by the needles 1 and 2 which effectively indicate the pilot's lateral position with respect to the two landing field stations.

The broader principles of my present invention are not dependent upon the specific automatic receiver unit disclosed for operating the dual indicator system. However, the success of the invention depends upon the use of a rapidly operating and accurate automatic direction indicating receiver unit such as I have hereinabove disclosed. The speed of loop orientation by the receiver unit is preferably at a rate of the order of 125 to 150 degrees per second without sacrificing accuracy in directional positioning of the loop antenna and its corresponding indicator needle. Such rate of operation results in completion of bearings on the transmitters well within the preferred one-third of a second period of transmission of the stations.

Although specific embodiment of the invention has been shown and described to illustrate the application of the principles thereof, it will be obvious that the invention may be otherwise embodied without departing from such principles.

What is claimed is:

1. A radio directional receiving system comprising two rotatable directional antennae; a single receiver unit, common to both of said antennae, for automatically orienting a connected one of said directional antennae to a stable bearing position with respect to correspondingly received radio signals; an indicator connected with each of said directional antennae for pointing out their angular orientation; and relay means re-

sponsive to successively received radio signals for correspondingly successively connecting said directional antennae to said single receiver unit for individual orientation to obtain directional bearings on the separately transmitted radio signals, one of said directional antenna normally being in connection with said receiver unit during inaction of said relay means for giving directional bearings on a single transmitted radio signal.

5 2. A radio directional receiving system comprising two rotatable directional antennae; a single receiver unit, common to both of said antennae, for automatically orienting a connected one of said directional antennae to a stable bearing position with respect to correspondingly received radio signals; an indicator electrically connected with each of said directional antennae for pointing out their angular orientation, said indicators being coaxially arranged; relay means responsive to successively received radio signals for correspondingly successively connecting said directional antennae to said single receiver unit for individual orientation to obtain directional bearings on the separately transmitted radio signals, one of said directional antenna normally being in connection with said receiver unit during inaction of said relay means for giving directional bearings on a single transmitted radio signal; and switching means for disconnecting the associated indicator from the normally unconnected directional antenna and connecting it with the indicator of said normally connected antenna, whereby both indicators give identical directional readings corresponding to the orientation of said connected directional antenna.

3. A radio directional receiving system comprising two rotatable directional antennae; a single receiver unit, common to both of said antennae, for automatically orienting a connected one of said directional antennae to a stable bearing position with respect to correspondingly received radio signals; a dual position indicator having a pair of indicating elements each connected to one of said directional antennae for pointing out their angular orientation; and a device responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said device for giving directional bearings on a single transmitted radio signal.

4. A radio directional receiving system comprising two rotatable directional antennae; a single receiver unit, common to both of said antennae, for automatically orienting a connected one of said directional antennae to a stable bearing position with respect to correspondingly received radio signals; two position transmitters each connected to one of said antennae for tele-metering its angular orientation; a pair of position indicators each connected to one of said position transmitters; and relay means responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said relay means for giving directional bearings on a single transmitted radio signal.

70 5. A radio directional receiving system com-

prising two rotatable directional antennae; a single receiver unit, common to both of said antennae, for automatically orienting a connected one of said directional antennae to a stable bearing position with respect to correspondingly received radio signals; two position transmitters each connected to one of said antennae for tele-metering its angular orientation; a dual position indicator having a pair of coaxial indicating elements each electrically connected to one of said position transmitters; relay means responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said relay means for giving directional bearings on a single transmitted radio signal; and switch means for connecting both of said indicating elements in parallel to the position transmitter connected to the antenna normally connected to said receiver unit, whereby both indicating elements give identical directional readings corresponding to the orientation of said connected directional antenna.

6. A radio directional receiving system comprising two rotatable directional antennae; a single receiver unit, common to both of said antennae, for automatically orienting a connected one of said directional antennae to a stable bearing position with respect to correspondingly received radio signals; an indicator connected with each of said directional antennae for pointing out their angular orientation; and a device responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said device for giving directional bearings on a single transmitted radio signal; said device including a solenoid connected to said unit, a first set of contacts connected to one of said antennae and its orienting means, a second set of contacts connected to the other antenna and its orienting means, and movable armatures connected to said unit and operatively associated with said solenoid.

7. A radio directional receiving system comprising two rotatable directional antennae; a single receiver unit, common to both of said antenna, for automatically orienting a connected one of said directional antennae to a stable bearing position with respect to correspondingly received radio signals; an indicator electrically connected with each of said directional antennae for pointing out their angular orientation; a device responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said device for giving directional bearings on a single transmitted radio signal; said device including a solenoid connected to said unit, a first set of contacts connected to one of said antennae and its orienting means, a second set of contacts connected to the other antenna and its orienting means, and movable armatures connected to said unit and operatively associated with said sole-

noid; said solenoid normally being energized to retain its armatures in engagement with one set of contacts to normally connect said one antenna to said unit.

5 8. A radio directional receiving system comprising two rotatable directional antennae; a single receiver unit, common to both of said antennae, for automatically orienting a connected one of said directional antennae to a stable bearing position with respect to correspondingly received radio signals; an indicator electrically connected with each of said directional antennae for pointing out their angular orientation, said indicators being coaxially arranged; a device responsive to 10 successively received radio signals for correspondingly successively connecting said directional antennae to said receiver unit for individual orientation to obtain directional bearings on the separately transmitted radio signals, one of said directional antenna normally being in connection with said receiver unit during inaction of said device for giving directional bearings on a single transmitted radio signal; said device including a solenoid connected to said unit, a first set of contacts connected to one of said antennae and its orienting means, a second set of contacts connected to the other antennae and its orienting means, and movable armatures connected to said unit and operatively associated with said sole- 15 noid; said solenoid normally being energized to retain its armatures in engagement with one set of contacts to normally connect said one antenna to said unit; and switching means for disconnecting the associated indicator from the normally unconnected directional antenna and connecting said associated indicator with the indicator of said normally connected antenna, whereby both indicators give identical directional readings corresponding to the orientation of said connected directional antenna.

40 9. A radio directional receiving system comprising two rotatable directional antennae; a single receiver unit, common to both of said antennae, for automatically orienting a connected one of said directional antennae to a stable bearing position with respect to correspondingly received radio signals; a dual position indicator having a pair of indicating elements each connected to one of said directional antennae for pointing out 45 their angular orientation; relay means responsive to successively received radio signals for correspondingly successively connecting said directional antennae to said receiver unit for individual orientation to obtain directional bearings on the separately transmitted radio signals, one of said directional antenna normally being in connection with said receiver unit during inaction of said relay means for giving directional bearings on a single transmitted radio signal; said relay means including a solenoid connected to said unit, a first set of contacts connected to one of said antennae and its orienting means, and movable armatures connected to said unit and operatively associated with said solenoid; said sole- 50 noid normally being energized to retain its armatures in engagement with one set of contacts to normally connect said one antenna to said unit.

60 10. In a radio guidance system incorporating two spaced and successively radiating transmitters having the same carrier frequency with the signals of one transmitter being tone modulated, two rotatable directional antennae; a receiver unit for automatically orienting a connected one of said directional antennae to a stable bearing 65 position with respect to correspondingly received

75

radio signals, said receiver unit being tuned to the common carrier frequency of the two successively radiating signal transmitters; an indicator connected with each of said directional antennae for pointing out their angular orientation; one of said directional antennae normally being in connection with said receiver unit during reception by said unit of unmodulated signals from one of the transmitters for giving directional bearings on a single transmitted radio signal; and selectively operable means effective upon reception by said units of tone modulated signals from the other transmitter to connect the other antenna to said unit for obtaining individual bearing indications on each of the transmitters.

11. In a radio guidance system incorporating two spaced and successively radiating transmitters having the same carrier frequency with the signals of one transmitter being tone modulated, two rotatable directional antennae; a receiver unit for automatically orienting a connected one of said directional antennae to a stable bearing position with respect to correspondingly received radio signals, said receiver unit being tuned to the common carrier frequency of the two successively radiating signal transmitters; an indicator connected with each of said directional antennae for pointing out their angular orientation; one of said directional antenna normally being in connection with said receiver unit during reception by said unit of unmodulated signals from one of the transmitters for giving directional bearings on a single transmitted radio signal; a device including a solenoid connected to said unit, a first set of contacts connected to one of said antennae and its orienting means, a second set of contacts connected to the other antennae and its orienting means, and movable armatures connected to said unit and operatively associated with said solenoid, said solenoid normally being energized to retain its armatures in engagement with one set of contacts to normally connect said one antenna to said unit during reception by said unit of unmodulated signals from one of the transmitters; and selectively operable means effective upon reception by said units of tone modulated signals from the other transmitter to effect de-energization of said solenoid to connect the other antenna to said unit for obtaining individual bearing indications on each of the transmitters.

12. In a radio guidance system incorporating two spaced and successively radiating transmitters having the same carrier frequency with the signals of one transmitter being tone modulated, two rotatable directional antennae; a receiver unit for automatically orienting a connected one of said directional antennae to a stable bearing position with respect to correspondingly received radio signals, said receiver unit being tuned to the common carrier frequency of the two successively radiating signal transmitters; an indicator connected with each of said directional antennae for pointing out their angular orientation; one of said directional antenna normally being in connection with said receiver unit during reception by said unit of unmodulated signals from one of the transmitters for giving directional bearings on a single transmitted radio signal; a device including a solenoid connected to said unit, a first set of contacts connected to one of said antennae and its orienting means, a second set of contacts connected to the other antenna and its orienting means, and movable armatures connected to said unit and operatively

associated with said solenoid, said solenoid normally being energized to retain its armatures in engagement with one set of contacts to normally connect said one antenna to said unit during reception by said unit of unmodulated signals from one of the transmitters; selectively operable tone pass filter means effective upon reception by said units of tone modulated signals from the other transmitter to effect deenergization of said solenoid to connect the other antenna to said unit for obtaining individual bearing indications on each of the transmitters.

13. In a radio guidance system incorporating two spaced and successively radiating transmitters having the same carrier frequency with the signals of one transmitter being tone modulated, two rotatable directional antenna; a receiver unit for automatically orienting a connected one of said directional antennae to a stable bearing position with respect to correspondingly received radio signals, said receiver unit being tuned to the common carrier frequency of the two successively radiating signal transmitters; a dual position indicator having a pair of indicating elements each electrically connected to one of said directional antennae for pointing out their angular orientation; one of said directional antenna normally being in connection with said receiver unit during reception by said unit of unmodulated signals from one of the transmitters for giving directional bearings on a single transmitted radio signal; a device including a solenoid connected to said unit, a first set of contacts connected to one of said antennae and its orienting means, and movable armatures connected to said unit and operatively associated with solenoid, said solenoid normally being energized to retain its armatures in engagement with one set of contacts to normally connect said one antenna to said unit during reception by said unit of unmodulated signals from one of the transmitters; selectively operable tone pass filter means effective upon reception by said unit of tone modulated signals from the other transmitter to effect de-energization of said solenoid to connect the other antenna to said unit for obtaining individual bearing indications on each of the transmitters.

14. In a radio guidance system incorporating two spaced and successively radiating transmitters having the same carrier frequency with the signals of one transmitter being tone modulated, two rotatable directional antennae; a receiver unit for automatically orienting a connected one of said directional antennae to a stable bearing position with respect to correspondingly received radio signals, said receiver unit being tuned to the common carrier frequency of the two successively radiating signal transmitters; two position transmitters each connected to one of said antennae for telemetering its angular orientation; a dual position indicator having a pair of coaxial indicating elements each electrically connected to one of said position transmitters; one of said directional antenna normally being in connection with said receiver unit during reception by said unit of unmodulated signals from one of the transmitters for giving directional bearings on a single transmitted radio signal; a device including a solenoid connected to said unit, a first set of contacts connected to one of said antennae and its orienting means, a second set of contacts connected to the other antenna and its orienting means, and movable armatures connected to said unit and operatively associated with said solenoid, said solenoid normally being

energized to retain its armatures in engagement with one set of contacts to normally connect said one antenna to said unit during reception by said unit of unmodulated signals from one of the transmitters; selectively operable tone pass filter means effective upon reception by said unit of tone modulated signals from the other transmitter to effect deenergization of said solenoid to connect the other antenna to said unit for obtaining individual bearing indications on each of 10

the transmitters; and switching means for disconnecting the associated indicating element from the normally unconnected directional antenna and connecting said associated indicating element with the indicating element of said normally connected antenna, whereby both indicating elements give identical directional readings corresponding to the orientation of said connected directional antenna.

WILLIAM P. LEAR.
